SLINGSHOT SIDE SADDLE
SUBSTRUCTURECROSS-REFERENCE TO RELATED
APPLICATION

This application is a continuation of U.S. application Ser. No. 14/616,234 filed Feb. 6, 2015, which is a continuation in part which claims priority from U.S. application Ser. No. 14/180,049 filed Feb. 13, 2014, itself a non-provisional application which claims priority from U.S. provisional application No. 61/764,259 filed Feb. 13, 2013.

FIELD OF THE DISCLOSURE

The present disclosure relates generally to drilling rigs, and specifically to slingshot rig structures for land drilling in the petroleum exploration and production industry.

BACKGROUND OF THE DISCLOSURE

Land-based drilling rigs may be configured to be traveled from location to location to drill multiple wells within the same area known as a wellsite. In certain situations, it is necessary to travel across an already drilled well for which there is a well-head in place. Further, mast placement on land-drilling rigs may have an effect on drilling activity. For example, depending on mast placement on the drilling rig, an existing well-head may interfere with the location of land-situated equipment such as, for instance, existing well-heads, and may also interfere with raising and lowering of equipment needed for operations.

SUMMARY

The present disclosure provides for a land based drilling rig. The land based drilling rig may include a first and a second lower box, the lower boxes positioned generally parallel and spaced apart from each other. The land based drilling rig may further include a drill floor. The drill floor may be coupled to the first lower box by a first strut, the first lower box and first strut defining a first substructure. The drill floor may also be coupled to the second lower box by a second strut, the second lower box and second strut defining a second substructure. The struts may be hingedly coupled to the drill floor and hingedly coupled to the corresponding lower box such that the drill floor may pivot between an upright and a lowered position. The drill floor may include a V-door oriented to generally face one of the substructures.

The present disclosure also provides for a land based drilling rig. The land based drilling rig may include a first and a second lower box, the lower boxes positioned generally parallel and spaced apart from each other. The land based drilling rig may further include a drill floor. The drill floor may be coupled to the first lower box by a first strut, the first lower box and first strut defining a first substructure. The drill floor may also be coupled to the second lower box by a second strut, the second lower box and second strut defining a second substructure. The struts may be hingedly coupled to the drill floor and hingedly coupled to the corresponding lower box such that the drill floor may pivot between an upright and a lowered position. The drill floor may include a V-door oriented to generally face one of the substructures. The land based drilling rig may further include a mast coupled to the drill floor. The land based drilling rig may further include a tank support structure

2

affixed to the first or second substructure. The tank support structure may include a tank and mud process equipment. The land based drilling rig may further include a grasshopper positioned to carry cabling and lines to the drilling rig. The grasshopper may be positioned to couple to the drill floor generally at a side of the drill floor, and the side of the drill floor to which the grasshopper couples may face towards the first or second substructure.

BRIEF DESCRIPTION OF THE DRAWINGS

The summary and the detailed description are further understood when read in conjunction with the appended drawings. For the purpose of illustrating the present disclosure, there are shown in the drawings exemplary embodiments of said disclosure; however, the disclosure is not limited to the specific methods, compositions, and devices disclosed. In addition, the drawings are not necessarily drawn to scale. In the drawings:

10 FIG. 1 is a side elevation from the driller's side of a drilling rig consistent with at least one embodiment of the present disclosure.

15 FIG. 2 is an overhead view of a drilling rig consistent with at least one embodiment of the present disclosure.

20 FIG. 3 is a perspective view of a drilling rig consistent with at least one embodiment of the present disclosure.

DETAILED DESCRIPTION

30 The present disclosure may be understood more readily by reference to the following detailed description, taken in connection with the accompanying figures, which form a part of this disclosure. It is to be understood that this disclosure is not limited to the specific devices, methods, applications, conditions or parameters described and/or shown herein, and that the terminology used herein is for the purpose of describing particular embodiments by way of example only and is not intended to be limiting of the present disclosure. Also, as used in the specification, including the appended claims, the singular forms "a," "an," and "the" include the plural, and reference to a particular numerical value includes at least that particular value, unless the context clearly dictates otherwise. The term "plurality," as used herein, means more than one.

35 40 FIG. 1 depicts a side elevation of drilling rig 10 from the "driller's side" consistent with at least one embodiment of the present disclosure. Drilling rig 10 may include drill rig floor 20, right substructure 30, and left substructure 40. Right and left substructures 30, 40 may support drill rig floor 20. Mast 50 may be coupled to drill rig floor 20. As would be understood by one having ordinary skill in the art with the benefit of this disclosure, the terms "right" and "left" as used herein are used only to refer to each separate substructure to simplify discussion, and are not intended to limit this disclosure in any way.

45 V-door side 22 of drilling rig 10 may be located over right substructure 30. The V-door side 52 of mast 50 may correspondingly face right substructure 30. Pipe handler 24 may be positioned to carry piping through a V-door as understood in the art positioned on V-door side 22 of drilling rig 10. In some embodiments, grasshopper 26 may be positioned to carry cabling and lines to drilling rig 10. In other embodiments (not shown), V-door side 22 and mast V-door side may face left substructure 40. In some embodiments, as depicted in FIG. 1, blow out preventer 90 may be located between left substructure 40 and right substructure 30, i.e. drilling rig 10 may be centered over a wellbore.

50 55 60 65 66

In some embodiments, tank support structure **80** and tanks **70** may be included in drilling rig **10**. Tank support structure **80** may be affixed to right substructure **30** or left substructure **40** by means known to those of ordinary skill in the art with the benefit of this disclosure, including, but not limited to, welding and bolting. As shown in FIG. 1, tank support structure **80** may be affixed to left substructure **40**. Tank support structure **80** may be located on the opposite substructure from V-door side **22** of drilling rig **10**. Tanks **70** may, for example, be mud tanks, auxiliary mud tanks, or other tanks useful in drilling operations and may be located within tank support structure **80**. In some embodiments, mud process equipment **100** may also be mounted within tank support structure **80**. Mud process equipment may include, for example, shakers, filters, and other equipment associated with the use of drilling mud.

FIG. 2 depicts an overhead view of drilling rig **10** consistent with at least one embodiment of the present disclosure in which V-door side **22** of drilling rig **10**, drill rig floor **20**, and tank support structure **80** are shown. In some embodiments, choke manifold **102** may likewise be located on drill rig floor **20**. In some embodiments, accumulator **104** may likewise be located on drill rig floor **20**. In some embodiments, accumulator **104** may be a Koomey Unit as understood in the art.

In some embodiments, substructures **30**, **40** may be fixed as depicted in FIGS. 1, 2. In some embodiments, as depicted in FIG. 3, substructures **30'**, **40'**, may pivotably support drill rig floor **20**. Drill rig floor **20** may be pivotably coupled to one or more lower boxes **130** by a plurality of struts **140** together forming substructures **30'**, **40'**. Lower boxes **130** may support drill rig floor **20**. Lower boxes **130** may be generally parallel to each other and spaced apart. Struts **140** may be hingedly coupled to drill rig floor **20** and to lower boxes **130**. In some embodiments, struts **140** may be coupled to lower boxes **130** and drill rig floor **20** such that they form a bar linkage therebetween, allowing relative motion of drill rig floor **20** relative to lower boxes **130** while maintaining drill rig floor **20** parallel to lower boxes **130**. Thus, drill rig floor **20** may be moved from an upper position as shown in FIG. 3 to a lower position while remaining generally horizontal.

In some embodiments, the movement of drill rig floor **20** may be driven by one or more hydraulic cylinders **150**. In some embodiments, when in the upright position, one or more diagonals **160** may be coupled between drill rig floor **20** and lower boxes **130** to, for example and without limitation, maintain drill rig floor **20** in the upright position.

In some embodiments, with reference to FIGS. 1-3, as they are mounted directly to a substructure (**30** or **40**) of drilling rig **10**, one or more pieces of equipment may travel with drilling rig **10** during a skidding operation. For example and without limitation, equipment may include tanks **70**, mud process equipment **100**, choke manifold **102**, accumulator **104**, mud gas separators, process tanks, trip tanks, drill line spoolers, HPU's, VFD, or driller's cabin **106**. As such any pipe or tubing connections between or taken from tanks **70**, mud process equipment **100**, choke manifold **102**, and/or accumulator **104** may remain connected during the skidding operations. This arrangement may allow, for example, more rapid rig disassembly ("rigging-down") and assembly (or "rigging-up") of drilling rig **10** before and after a skidding operation.

Additionally, by facing V-door side **22** of drilling rig **10** toward one of the substructures **30**, **40**, equipment and structures that pass through the V-door **23** or to drill floor **20**

from V-door side **22** of drilling rig **10** may, for example, be less likely to interfere with additional wells in the well field.

One having ordinary skill in the art with the benefit of this disclosure will understand that the specific configuration depicted in FIGS. 1-3 may be varied without deviating from the scope of this disclosure.

Those skilled in the art will appreciate that numerous changes and modifications can be made to the preferred embodiments of the present disclosure and that such changes and modifications can be made without departing from the spirit of said disclosure. It is, therefore, intended that the appended claims cover all such equivalent variations as fall within the true spirit and scope of said disclosure.

What is claimed is:

1. A land based drilling rig comprising:
a first and second lower box, the lower boxes positioned generally parallel and spaced apart from each other;
a drill rig floor coupled to the first lower box by a first strut, the first lower box and first strut defining a first substructure, the drill rig floor coupled to the second lower box by a second strut, the second lower box and second strut defining a second substructure, the struts hingedly coupled to the drill rig floor and hingedly coupled to the corresponding lower box such that the drill rig floor pivots between an upright and a lowered position, the drill rig floor including a V-door, the V-door oriented perpendicularly to a long axis of one of the substructures;

a first and second hydraulic cylinder, the first and second hydraulic cylinders connected to the drill rig floor and the lower boxes; and
diagonals coupled between the drill rig floor and first and second substructures.

2. The land based drilling rig of claim 1, further comprising a mast coupled to the drill rig floor.

3. The land based drilling rig of claim 2, wherein the mast further comprises a V-door side and wherein the V-door side of the mast faces the first or second substructure.

4. The land based drilling rig of claim 1, further comprising a grasshopper positioned to carry cabling and lines to the drilling rig, the grasshopper positioned to couple to the drill rig floor generally at a side of the drill rig floor, and the side of the drill rig floor to which the grasshopper couples is oriented perpendicularly to a long axis of the first or second substructure.

5. The land based drilling rig of claim 1, wherein the first and second substructures are adapted to be traveled through a wellsite.

6. The land based drilling rig of claim 1, further comprising a choke manifold, the choke manifold positioned on the drill rig floor.

7. The land based drilling rig of claim 6, further comprising an accumulator, the accumulator positioned on the drill rig floor.

8. The land based drilling rig of claim 1, further comprising one or more of a drill line spooler, an HPU, a VFD, a driller's cabin, hydraulic unit, trip tank, process tank, or mud gas separator adapted to be traveled with the land based drilling rig.

9. The land based drilling rig of claim 8, wherein the drill line spooler, HPU, VFD, driller's cabin, hydraulic unit, trip tank, process tank, or mud gas separator is mounted directly to the first substructure or second sub structure.

10. A method comprising:
positioning a first and second lower box generally parallel and spaced apart from each other;

coupling a drill rig floor to the first lower box by a first strut, the first lower box and first strut defining a first substructure, the drill rig floor including a V-door, the V-door oriented perpendicularly to a long axis of one of the substructures;

coupling the drill rig floor to the second lower box by a second strut, the second lower box and second strut defining a second substructure, the struts hingedly coupled to the drill rig floor and hingedly coupled to the corresponding lower box;

10 pivoting the drill rig floor between an upright and a lowered position using a first and second hydraulic cylinders, the first and second hydraulic cylinders connected to the lower boxes;

pivoting the drill rig floor between the lowered position and the upright position using the first and second hydraulic cylinders; and

15 coupling diagonals between the drill rig floor and first and second substructures.

11. The method of claim **10**, further comprising coupling a mast to the drill rig floor.

12. The method of claim **11**, wherein the mast further comprises a V-door side and wherein the V-door side of the mast is oriented perpendicularly to a long axis of one of the substructures.

13. The method of claim **10**, further comprising positioning a grasshopper to carry cabling and lines to the drilling rig, the grasshopper positioned to couple to the drill rig floor generally at a side of the drill rig floor, and the side of the drill rig floor to which the grasshopper couples oriented perpendicularly to a long axis of the first or second substructure.

14. The method of claim **10**, further comprising traveling the first and second substructures through a wellsite.

15. The method of claim **10**, further comprising traveling one or more of an accumulator, choke manifold, drill line spooler, HPU, VFD, driller's cabin, hydraulic unit, trip tank, process tank, or mud gas separator with the first and second substructures.
